DUPLICATING APPARATUS

Robert F. Morrison, Oak Park, Ill., assignor to
Ditto, Incorporated, Chicago, Ill., a corporation
of West Virginia

Application August 31, 1940, Serial No. 354,981

12 Claims. (Cl. 101—132.5)

This invention relates to duplicating machines and in particular to means for controlling the operation thereof.

The particular type of duplicating machine shown is known as the wet process or spirit duplicator. Such machines are usually provided with two adjustments, one for adjusting the pressure between the drum and the pressure roll and the other for regulating the amount of solvent that is supplied to the moistening means.

In devices of this sort a copy sheet is moistened and fed between the drum and the pressure roll. A master sheet is secured to the drum, the characters of the master sheet being written in reverse in a soluble ink. The solvent with which the copy sheet is moistened dissolves a small amount of the ink forming the characters on the master sheet. The legibility and clearness of the characters formed on the copy sheet are determined in large measure by the amount of solvent supplied to the copy sheet and the degree of pressure between the pressure roll and the drum.

The drum may be made of metal and the pressure roll of a slightly resilient material, and in order to secure efficient operation of the machine and long life of the pressure roll it is desirable to relieve the pressure upon the pressure roll while the machine is not in use.

The moistening means employed in certain types of machines require priming. The priming means in the machine herein described is a part of the solvent regulating means. In machines of this type it is desirable to perform the priming operation manually inasmuch as over priming will ruin the master sheet.

An object of my invention is to provide improved means for controlling the operation of a wet process duplicating machine.

A further object is to provide improved means for causing the release of the pressure between the pressure roll and the drum while the machine is not in operation.

A further object is to provide improved means for controlling the amount of solvent supplied to the moistening means.

A still further object is to provide means whereby the priming operation must be performed manually and whereby operation of the machine is prevented when the solvent control means is adjusted for priming.

Another object is to prevent operation of the machine when the adjusting means therefor is not set for proper operation of the machine.

Referring now to the drawings in which like reference numerals represent like parts—

Fig. 1 is a sectional elevation through a duplicating machine which represents a preferred embodiment of my invention;

Fig. 2 is a sectional elevation along the line 2—2 of Fig. 1;

Fig. 3 is a broken end elevation taken along the line 3—3 of Fig. 2;

Fig. 4 is a diagrammatic representation of the control means and of the electric circuit forming a part thereof;

Fig. 5 is a sectional elevation similar to Fig. 1 but showing only a portion thereof in detail, certain elements being omitted for the purpose of clarity;

Fig. 6 is a detailed section taken along the line 6—6 of Fig. 5 showing the liquid regulating means;

Fig. 7 is a detailed section taken along the line 7—7 of Fig. 5;

Fig. 8 is a detailed section taken along line 8—8 of Fig. 5 showing the pressure regulating means;

Fig. 9 is an enlarged sectional elevation taken along the line 9—9 of Fig. 2; and

Fig. 10 is an elevation of a portion of the machine taken along line 10—10 of Fig. 1.

Reference numeral 11 indicates the side frame members of a duplicating machine which is also provided with a front frame member 12 and a rear frame member 13. A drum 14 is suitably journaled in the side frame members of the machine. A pressure roll 15 is mounted for cooperation with the drum. A moistening and upper feed roll 16 may be suitably journaled in the side frames of the machine. A lower feed roll 17 is suitably mounted for cooperation therewith.

A moistener, indicated generally by reference numeral 18, is suitably mounted adjacent the upper feed roll and moistening roll and serves to apply a thin film of moisture to the surface of that roll. The moistener may be any one of a number of types, the one being shown herein being of the type in which solvent is sprayed directly onto the feed roll by means of a pump 21 and in which a felt 19 is used to distribute the solvent over the face of the rotating feed roll.

A tank 20 is provided at the rear portion of the machine in which the pump 21 is mounted. The pump plunger 22 extends upwardly from the tank, said plunger being adapted to be raised, by means hereinafter described, on its inoperative stroke and being provided with a spring, indicated at 22a, to urge the plunger downwardly for

its operative stroke. A conduit 23 leads from the pump 21 to the moistener 18. The tank is provided with a filling pipe 24 and a liquid level gauge 25.

A feed tray 26 is positioned over the tank at the rear end of the machine and a receiving tray 27 is mounted at the front end of the machine.

A motor 28 is suitably mounted at the rear end of the machine and is provided with a pulley 29 over which a belt 30 passes to drive the pulley 31. A pulley 32 associated with pulley 31 drives pulley 34 by means of belt 33. A pinion 35 is affixed to pulley 34 and meshes with gear 36 which is affixed to the drum 14. A gear 37 is associated with the drum and drives an intermediate pinion 38 which in turn meshes with a pinion 39 which is secured to the upper feed roll 16 so that the feed roll may be driven from the drum. Suitable intermittent driving means may be interposed between the feed roll and the gear 37 or between the gear 37 and the drum so that the feed roll may remain stationary during a portion of the drum's rotation in order that the copy sheets may be positioned with respect to the drum. Such intermittent driving means are not a part of this invention and are not disclosed herein.

The reduced end of the pressure roll 15 is journalled in a bearing 40 which is carried on a pivoted arm 41 as shown in Figs. 1 and 9. Both ends of the pressure roll are similarly mounted and the corresponding pivoted arms 41 are connected by a cross member 42 which is provided intermediate its ends with a downwardly extending portion 43 carrying a notched collar 44 at its lower extremity. A washer 45 cooperates with the notched collar 44 and is mounted on a stud 46. A coil spring 47 surrounds the stud and is confined between the washer 45 and the adjusting nuts 48. The stud which passes through the coil spring and the collar 44 is mounted at one end on a sleeve 49.

An eccentrically mounted shaft 50 is suitably journalled in the side frame members 11 by means of the journals 51, as shown in Fig. 8. A manually operated knob 73 is secured to the eccentric shaft 50 exteriorly of the side frame member 11 and is provided with a pointer 52 which cooperates with indicia 53 formed on the side frame member 11. It will be seen that rotation of the knob 73 so that the pointer progresses from the "O" point, as indicated by the indicia in Fig. 9, in the clockwise direction, will cause rotation of the eccentric shaft in such a manner as to draw the sleeve 49 to the right, as viewed in Fig. 9, against the compression of spring 47 whereby an increased force is exerted on the lever comprising the collar 44 and members 43, 42 and 41. This causes the pressure roll 15 to be resiliently urged against the drum 14 with a force which is roughly indicated by the cooperation of the pointer 52 and the indicia 53.

The operation of the electric motor is controlled by a suitable switch or contact means 54 which, as shown in Fig. 7, is secured to the side frame 11 by means of a mounting member 69. This switch may be one of a number of types but I found that satisfactory results are obtained by the use of that switch which is sold under the trade-name "Burgess Micro Switch." The switch 54 is provided with an actuating plunger 55 which is biased upwardly and outwardly from the switch proper to a closed circuit position. An actuating arm 56 is suitably

pivoted on a stud 57 and is provided with a horizontal extension 58 which cooperates with the plunger 55 so that when the arm is depressed against the tension of the spring 59 the motor circuit will be opened. The spring 59 normally biases the actuating arm 56 to closed circuit position.

The lower feed roll 17 is suitably journalled in a bearing 60, as shown in Fig. 1, which is carried on a pivoted arm 61. A link 62 is associated with the arm 61 and is provided with a slot 63 therein which cooperates with a stud 64 extending inwardly from the side frame member 11 so that the motion of the link is confined to a more or less longitudinal direction. A spring 65 has its upper end secured to a stud or tie rod 66 and has its lower end secured to a member 67 which is mounted at the lower portion of the link 62. The member 67 is provided with a plurality of slots so that the tension of the spring 65 may be regulated to urge the lower feed roll against the upper feed roll with a predetermined force.

A pin 70 is provided on link 62 which is engaged by a projection 71 extending outwardly from the eccentric shaft 50 or from the reduced end portion 51 thereof. When the pointer is turned from the "O" position, as indicated in Fig. 9, to the "R" or release position the projection 71 comes into contact with the pin 70 and urges the link 62 downwardly so as to release the pressure on the lower feed roll, and at the same time the member 67 or the lower portion of the link 62 bears on a stud 72 so as to cause the actuating arm 56 on which the stud 72 is mounted to be depressed. This opens the motor circuit. It will be seen consequently that when it is desired to shut off the motor that the pressure dial is rotated to the release position and this automatically causes the release of pressure on both the pressure roll 15 and the lower feed roll 17.

Adjusting nuts 75 are provided at the upper end of the pump plunger 22 and a washer 76 is located on the plunger immediately below the adjusting nuts, which washer forms a bearing surface for the end of the pump lever 77. The pump lever 77 is pivoted upon a stud or tie rod 78 and the lower end of the lever terminates in a roller 79, as shown in Fig. 9. A forwardly extending actuating arm 80 is also pivoted on stud 78 and is suitably secured to the pump lever 77. A cam rider in the form of a roller 81 is provided at the upper end of the actuating arm and cooperates with a cam 82 which is secured to the drum. It will be seen that with every revolution of the drum the cam 82 will cause the cam roller 81 and the pump lever 77 to be gradually rotated in the clockwise direction, thereby elevating the pump plunger 22. At a predetermined point in the drum's rotation the drop portion 74 of the cam 82 will permit the spring which is associated with the pump plunger 22 to force the plunger downwardly and supply a measured amount of solvent to the moistener 18. The quantity of solvent thus supplied is determined by regulating the length of the pump stroke.

As indicated in Fig. 6, a stub shaft 83 is journalled in a boss 84 of the side frame 11 and a cam 85 is secured to the stub shaft. The substantially spirally shaped surface of the cam cooperates with the roller 79 to limit the clockwise rotation of the pump lever 77, as shown in Fig. 9. This in turn limits the extent to

which the pump plunger may drop after the roller 81 has dropped off the drop portion 74 of the cam 85. The operative portion of the surface of cam 85 terminates at one end in a projection 86 which, as shown in the full line position in Fig. 5, limits the counterclockwise rotation of the cam 85. The other end of the operative portion of the cam surface terminates in a detent 87 which, as shown in the dotted line position in Fig. 5, serves to limit the clockwise rotation of the cam 85. In the full line position the pump plunger is raised to a position wherein the stroke is negligible and in which no solvent will be supplied to the moistener 18. In the dotted line position, however, the pump arm 17 is lowered so as to permit the pump to operate with full stroke, thereby supplying a maximum amount of solvent to the moistener.

A manually actuated knob 88 is secured to the stub shaft 83 exteriorly of the side frame 11 and carries a pointer 89 which cooperates with indicia 90 formed on the side frame member to indicate generally the position of the cam 85 and the length of the pump stroke.

During normal operation of the machine the roller 79 contacts the intermediate spirally shaped portion of the cam surface 85. However, after the machine has been standing idle for some time it is necessary to prime the same and this may be effected by turning the knob 88 and pointer 89 to the "P" or priming position. Rotation of the knob back and forth from the "P" position will cause the roller 79 to ride in and out of the detent portion 87, thereby causing reciprocation of the pump lever 17 and the pump plunger 22. A few of such manual priming strokes will be sufficient to condition the moistener for proper use. It will be seen however that if the motor is energized when the pointer is in the priming position that the pump will be operated at its full stroke thereby flooding the moistening means and ruining the master sheet unless the motor is again shut off after the drum has revolved three or four times.

To obviate this difficulty the cam 85 is provided with a projection 91 which is adapted to contact the horizontal extension 58 of the switch actuating arm 56. The projection 91 is so positioned that when the pointer is rotated to the "P" position the above mentioned contact between the projection 91 and the member 58 takes place, thereby causing the motor circuit to be opened. Consequently, no matter what the position of the pressure dial is, the motor cannot operate with the liquid dial set at "P". This insures that the priming will be performed manually.

The motor 28 is connected across the lead lines 92 by means of conductors 94. A lamp 93 is also connected across the lead lines in parallel with the motor and serves as an indicator. The switch 54 is in series with both the lamp and the motor and is connected to one of the lead lines by conductors 95. Reference to Fig. 4 will indicate the relationship of these parts to each other, as well as to the manually rotatable control shafts 50 and 83 and their associated switch actuating means.

As indicated in Figs. 1 and 10, the lamp 93 may be positioned beneath a housing 96 and a sight glass or lens 97 provided so that the circuit condition will be apparent to the operator.

A handle 98 may be provided for the actuation of the master sheet gripping means through the intermediation of the expanding cams 99. A 75

master sheet feed tray 100 may also be provided for cooperation with said gripping means. The details of this mechanism are not a part of this invention but are described in detail in Patent No. 2,195,491 issued April 2, 1940, to Alfred Marchev.

10 Certain types of duplicating machines are provided with a clutch between the motor and the drum. In such instances it may be desirable to associate clutch disengaging means with the actuating arm 56 rather than the switch 54 as shown herein. In other instances it may be desirable to provide a hand crank operated machine with such a clutch in combination with the control means herein disclosed.

15 While there have been shown and described certain embodiments of the invention, it is to be understood that it is capable of many modifications. Changes, therefore, may be made without departing from the scope of the invention as described in the appended claims, in which it is the intention to claim all novelty inherent in the invention as broadly as possible, in view of the prior art.

20 I claim:

1. A wet process duplicating machine comprising a drum, a co-acting pressure roll, a spring to urge said pressure roll into contact with said drum, a motor for rotating said drum, a switch for said motor and common control means for relaxing the tension on said spring and for actuating said switch so that the pressure between said pressure roll and said drum is automatically released when said motor is turned off.

2. A duplicating machine comprising a drum, driving means therefor, a co-acting pressure roll, feed rolls, means to urge said feed rolls into contact with each other, and means for regulating the pressure between said drum and said pressure roll, said means being operable to separate said feed rolls from each other and to cause said driving means to be rendered inoperative when set to a position wherein the pressure exerted by said pressure roll on said drum is relieved.

3. A duplicating machine comprising a drum, driving means therefor, moistening means, priming means for said moistening means, and control means to render said driving means inoperative during operation of said priming means.

4. A duplicating machine comprising driving means therefor, moistening means, a pump operated by said driving means, said pump including a reciprocating plunger, means for regulating the extent of reciprocation of said plunger, and means for rendering said driving means inoperative when said regulating means is set for the maximum plunger stroke.

5. A duplicating machine comprising a moistening means, a pump for supplying solvent to said moistening means, a plunger for said pump, a rotatable cam, means for rotating said cam, means actuated by said cam for causing reciprocation of said plunger, manually controlled means engaging said plunger for limiting the extent of said reciprocation, and means engaged by said manually controlled means for rendering said driving means inoperative when said control means is set to permit full stroke of said plunger.

6. Solvent control means for a duplicating machine comprising a pump, automatic means for operating said pump, manual means for operating said pump, said manual means being adapted to remain set in certain predetermined positions to limit the displacement of said pump, and

means associated with said manual means to render said automatic means inoperative when said manual means is set in a given predetermined position.

7. Moistening means for a duplicating machine comprising a moistening roller, liquid retaining means associated with said roller for maintaining a body of liquid in contact therewith, means including a pump for supplying liquid to said liquid retaining means, said pump comprising a plunger, a spring for actuating the operative stroke of said plunger, a pivoted member engaging said plunger for actuating the inoperative stroke thereof, automatic means for oscillating said pivoted member, manual means for oscillating said pivoted member, said manual means being so positioned as to engage said pivoted member and to regulate the amplitude of oscillation thereof when oscillated by said automatic means, and means for rendering said automatic means inoperative, said last named means being actuated by said manual means when said manual means is set to a position wherein it exercises no effective regulation over the oscillation of said pivoted member.

8. A duplicating machine comprising a drum and co-acting pressure roll, moistening means for copy sheets, means for regulating the pressure between said pressure roll and said drum, means for regulating the amount of solvent supplied to said moistening means, a motor for said duplicating machine, a switch in circuit with said motor, said switch being normally in closed circuit position, and means to operate said switch to open circuit position when said pressure regulating means is set to minimum pressure, or when said solvent regulating means is set to maximum solvent supply.

9. A duplicating machine comprising a drum and a co-acting pressure roll, a moistening and feed roll disposed adjacent the bite of said drum and pressure roll, a co-acting feed roll resiliently urged against said moistening and feed roll, means for regulating the pressure between said pressure roll and said drum, means for regulating the amount of moisture supplied to said moistening and feed roll, a source of power for driving said duplicating machine, means for disconnecting said machine from said source when either of said regulating means are set in certain positions, and means for separating said feed rolls when said pressure regulating means is set in power disconnecting position.

10. In a power driven wet process duplicating machine having solvent regulating means, pressure regulating means and power disconnecting means, control means comprising a member actuated either by setting said pressure regulating means to pressure release position or by setting said solvent regulating means to maximum solvent supply position to engage said power disconnecting means to operate the same.

10 11. A duplicating machine comprising a drum, a feed roll, driving means for said drum and said roll, a pressure roll for cooperation with said drum, a spring for urging said pressure roll against said drum, a second feed roll resiliently urged against said first feed roll, means for rendering said driving means inoperative, a member associated with said second feed roll and extending into proximity to said last named means, and manually adjustable means for regulating the tension of said spring and adapted, when adjusted to minimum tension, to engage said member to retract said second feed roll from contact with said first feed roll and to engage said inoperative rendering means whereby said drum and first feed roll may be stopped only after the release of the pressure exerted thereon by their respective contacting rolls.

12. A duplicating machine comprising a drum, a combined moistening and feed roll and means for supplying a film of solvent of regulated thickness to said combined moistening and feed roll, said means including a reciprocable pump plunger, driving means for said drum, said roll and said plunger, a pressure roll for cooperation with said drum, a spring for urging said pressure roll against said drum, a second feed roll resiliently urged against said combined moistening and feed roll, means for rendering said driving means inoperative, a member associated with said second feed roll and extending into proximity to said last named means, manually adjustable means for regulating the tension of said spring and adapted, when adjusted to minimum tension, to engage said member to retract said second feed roll from contact with said combined moistening and feed roll and to engage said inoperative rendering means, and second manually adjustable means for regulating the amplitude of reciprocation of said plunger and adapted, when adjusted to maximum amplitude, to engage said inoperative rendering means.

ROBERT F. MORRISON.
